Primary Examiner — J. Thorn, Sr.

(57) CLAIM

The ornamental design for a strap on harness underwear, as shown and described.

DESCRIPTION

FIG. 1 is a front perspective view of a strap on harness underwear design showing my new design.

FIG. 2 is a front view thereof.

FIG. 3 is a rear view thereof.

FIG. 4 is a left side view thereof.

FIG. 5 is a right side view thereof.

FIG. 6 is a rear perspective view thereof.

FIG. 7 is a front perspective view thereof, shown the state of use; and,

FIG. 8 is a front perspective view thereof, shown the state of removing front cover.

The broken lines in the drawings depict portions of the strap on harness title that form no part of the claimed design. The phallic object shown in FIG. 7 shown coming through the title depicts environment and forms no part of the claimed design.

1 Claim, 7 Drawing Sheets
